RECEPTACLE HOLDER

Alex E. Hunter, 2713 Pyramid Ave., Pittsburgh 27, Pa.

Filed Oct. 20, 1955, Ser. No. 541,606

3 Claims. (Cl. 248—121)

This invention relates to a receptacle holder and relates more particularly to a novel arrangement of a foldable and portable tray holder.

One object of my invention is to provide a tray holder which is easy to set up and which does not require a solid supporting structure for attachment thereto when in use.

Another important object of my invention is to provide a tray holder having a bottom supporting member adapted to utilize a portion of the users' weight for the purpose of holding it in a firm position.

A further object of my invention is to provide a foldable and portable tray holder of simplified construction comprising a minimum number of parts.

A still further object of my invention is to provide a compact portable tray holder onto which a receptacle such as a tray can easily be attached and held in firm position while in use.

These and other objects of my invention will appear from the following detailed description taken in connection with the accompanying drawings in which:

Figure 1 is a side elevation incorporating features of the invention and showing the folded tray holder in dot and dash lines.

Figure 2 is a detailed side elevation of the movable jaw assembly with attached tray (cut away view of tray).

Figure 3 is a side elevation as Figure 2 but showing the movable jaw assembly in open position.

Figure 4 is a rear elevation showing certain features of the movable jaw assembly and features of the hinging arrangement in dot and dash lines.

Figure 5 is a detailed view of the hinging feature taken from the inner side of the upright members shown in dot and dash lines in Figure 4.

Figure 6 is a front elevation of the movable jaw assembly.

Figure 7 is a front elevation of the invention showing a modification of my tray holder.

Figure 8 is a side elevation of Figure 7 showing the modified member for engaging the rim of a tray. The dot and dash lines indicate the operation of the modified member.

Similar numerals of reference denote like parts in the several figures of the drawings.

Referring to Figures 1 through 5, numeral 1 denotes a flat bottom member for supporting the apparatus in upright position. One end of this support is provided with brackets 2 and 3 as shown in Figure 4. Brackets 2 and 3 can be rigidly fixed to the bottom member such as by welding or by screws. The bracket denoted by numeral 2 is provided with horizontal and vertical channels or slots 4 and 5 respectively as shown more clearly in Figure 5 and forms part of the hinging assembly. The bracket indicated by 3 (see Figure 4) is provided with a nut and bolt 8 as shown. A pair of spring steel upright supports 6 and 7 are hingedly fixed to brackets 2 and 3 and form the hinging assembly of the bottom support member 1; they also support the movable jaw

2

assembly as will be described hereinafter. Spring steel upright support 6 connects with vertical slot 5 as shown in Figure 5 to lock the apparatus in upright position.

Brackets 2 and 3 (see Figure 4) are provided with holes for nut and bolt 8 and lug 9. Spring steel upright member 7 is likewise provided with a hole for nut and bolt 8. Lug 9 is fixed to spring steel member 6 such as by welding and connects bracket 2 to it through its hole. (See Figure 4.)

10 The upper mechanism of spring steel upright supports 6 and 7 comprise the movable jaw assembly of my tray holder and constitute the preferred embodiment. In Figures 1 and 4 numeral 11 denotes a channel which is formed of metal such as aluminum or steel and is adapted to secure spring steel upright supports 6 and 7 by means of a pair of nuts and bolts 12 and 13 on either side of the channel respectively. The spring steel upright supports and channel are provided with holes to receive the nut and bolt arrangement. The channel can obviously be secured to spring steel upright supports by other means, for example welding. It is also possible to machine an integral unit of this section. The arrangement of my invention, however, is simple and can be easily set up in the manner described. In the actual embodiment of my invention I have provided a pair of stop members 14 interposed on either side of channel 11 and on the outer side of spring steel upright supports 6 and 7 as shown in Figures 1, 3 and 4. Stop members 14 are constructed of a flat piece of metal having one edge resting flat against channel 11 and are rigidly fixed by nut and bolt pairs 12 and 13 to channel 11, and spring steel upright members 6 and 7. The upper edge of stop members 14 are fixed so that they are flush with a horizontal groove or recess 16 on aluminum or steel channel 11. The stop members and the recess in channel 11 form rests or shoulders 17. The construction of rest members 14, recess 16, and shoulders 17, is arranged to cooperate with the movable jaw assembly in holding a receptacle such as a tray.

35 In Figures 4 and 6 numeral 18 indicates a vertical slot on channel 11 which extends downwardly to approximately half of the length of the channel. This vertical slot is centered on the channel and is opened at the top to engage and cooperate with a member of the movable jaw assembly to be shown hereinafter.

Figures 1 through 4 and 6 demonstrate the movable jaw assembly of my tray holder. Numeral 21 indicates a pair of L-shaped members of flat metal joined to the rear of channel 11 such as by welding or screws and adapted to receive a handle 22 between them which is pivotally fixed by pin 23 to them as shown. Handle 22 is curved as at 24 for clearance only and provides a pivot or cam surface against channel 11. The curvature of handle 22 terminates as a short round end 25 which

55 is provided with a hole to receive a pin 26 onto which spring steel link 27 is arranged as demonstrated in Figures 1, 2 and 3. The spring steel link is attached to a pair of parallel movable arms 28 by pin and pin sleeve 29 secured inside of channel 11. Movable arms 28 are aligned above rest members 14 and are attached to the channel by a pin and pin sleeve 30. It should be noted that movable arms 28 are composed of flat pieces of metal which are slightly curved at the lower end 31 in order to fit evenly against rest members 14 as at 15.

60 If desired, the two movable arm members can be joined by a third pin and pin sleeve 32 as shown in Figures 1, 2 and 3.

65 Spring steel link 27 passes through vertical slot 18 of channel 11 and is attached to pin and pin sleeve 29 approximately at the center.

70 Figure 2 shows the movable jaw assembly holding the

tray 33 and shows the bead or rim of the tray at 34 positioned in horizontal recess or groove 16 of the channel 11. Tray 33 is a tray provided with the conventional rim or bead. It should be noted, however, that in this modification of my invention the movable jaw assembly can grip a tray not provided with the conventional rim or bead around its edge or periphery.

Figures 7 and 8 demonstrate another embodiment of my invention. In Figure 7 there is shown spring steel upright supports 6 and 7 and channel 41 of slightly different construction than channel 11 of my preferred embodiment. In this embodiment I provide the channel with recess or groove 42 so constructed that a portion of the channel proper curves or protrudes slightly over the recess as shown in 43. The channel is constructed so that its front edges taper slightly upwardly from the bottom as shown at 44. In this manner the configuration of the tray rests evenly on this surface.

A thin resilient or springlike piece of metal 45 is rigidly fixed on the rear of channel 41 by a nut and bolt pair 46 and 47 as shown. This resilient metal member is provided with a tapering round section that projects above channel 41 as shown at 48. Numerals 49 and 50 indicate two lugs rigidly fixed on the flat thin member and passing through holes in channel 41. These lugs are beveled on the upper edge as shown in 51 and 52 in Figures 7 and 8 and their ends project just slightly beyond the deep portion of groove or recess 42. Figure 8 shows a tray 53 with a bead 54 in clamped position. The dot and dash lines show how the tray is released or attached.

In actual operation the tray holder of my invention may be set up from its folded position (see dot and dash lines of Figure 1) by merely exerting pressure on the bottom part of spring steel upright support 6 such as by squeezing to cause disengagement from horizontal slot 4 (dot and dash lines of Figure 5). After the spring steel support has cleared the horizontal slot of bracket 2, the apparatus is opened to approximately 90°. At this point, spring steel upright support 6 comes into alignment with vertical slot 5 of bracket 2 and automatically slips into position locking the apparatus in upright position. Now, in order to fold the tray holder, a slight pressure is again exerted on spring steel upright support 6 to cause disengagement of the support from vertical slot 5 and the apparatus is swung to a folding position until the spring steel upright support locks in horizontal slot 4 of bracket 2.

When the apparatus is set up, handle 22 is raised upwardly to cause disengagement of arm members 28 and rest members 15 of the movable jaw assembly. The tray is then placed with its rim or groove 16 resting on shoulder 17, and flush against edge 15 of stop members 14. To lock the tray in position the handle is lowered downwardly until its edge rests flat on the rear of channel 11 as shown in Figure 2. Note also, that handle 22 swings or pivots about its curved portion or cam 24 to cause a tight grip on the tray.

Once the handle is resting evenly on the channel member in locked position (Figure 2) it is prevented from accidentally opening because of the gripping force of the jaw assembly. Thus when it is in locked position, the spring steel member 27 exerts a locking force which can be overcome only when the handle pivots or has been forced to pivot on channel member 11.

In the modified tray holder shown in Figures 7 and 8 a tray can be clamped in position by pushing member 48 rearwardly (as shown by the dot and dash lines of Figure 8) inserting the rim or bead of the tray in recess 42, and releasing member 48. In this case lugs 49 and 50 exert a locking force on the tray by exerting pressure on the lower side in contact with them. The lugs also exert an upward locking pressure on the tray by virtue of their beveled edges. These beveled edges contact the bead of the tray and exert a force upwardly and forwardly. The locking force is caused by resilient or

spring member 48. To disengage the tray, resilient member 48 is pushed back and the tray is slid out of its engaging position. The tapered edge 44 of channel 41 facilitates the removal and attachment of the tray since the edge and bead of the tray slide on this surface. When the tray is in position its edge rests evenly on edge 44 of channel 41.

In the preferred embodiment of my invention the tray is locked firmly by the jaw assembly and is stable against any upward or downward force exerted on it. Thus the tray cannot be disengaged by any accidental force exerted on it. The tray holder of the modification of my invention is stable against any downward force and will not disengage without the proper manipulation. It is also stable against any accidental force exerted in an upward direction but is not as securely gripped or clamped as in the preferred embodiment of my invention.

In constructing a tray holder in accordance with my invention I can construct a compact unit with light metal 20 and the like. Thus the bottom support member can consist of a light flat piece of metal or plastic approximately nine to twelve inches in length, about one eighth inch thick, and about three and one half to five inches in width. The spring steel supports can be from one eighth 25 of an inch to one fourth inch thick; they can be spaced from one to three inches and can be about ten to fifteen inches in length. A solid object can be interposed between the upright supports at about the middle to give them greater resiliency if desired. The channel provided 30 at the upper end of the spring steel upright members can be constructed so that its lower edge can swing freely over the free end of the bottom support member. In this manner the holder, when folded, occupies less space and can be folded into a more compact unit (see Figure 1).

Obviously any suitable dimensions can be used for the 35 various members of my tray holder and the dimensions given above are only for purpose of illustration and are not intended as limitations of my invention.

Although I have described certain preferred embodiments of my invention it should be understood that several other modifications will become apparent to persons skilled in the art. Thus for example, other modifications in the hinging arrangement of spring steel upright supports are readily apparent. For example, the two spring 45 steel upright members can be connected by a suitable bridge bearing a plunger or pin and a spring for actuating it. In this case the bottom support member is provided with, say, a tapered hole, or a small solid metal member with a tapered hole or other member for receiving the 50 plunger or pin.

The construction of my tray holder can be carried out with other solid materials besides metal. Thus part of the holder can be constructed of metal and part of plastics; or all metal, or plastics, or any suitable durable material. My invention resides in the provision of a tray 55 holder adaptable for various uses and not requiring a solid supporting structure for attachment thereto while in use.

A tray holder such as I have described will find many 60 uses and applications. One use would be in plant feeding operations or any place where tables are not provided, or where the use of tables would be expensive or cumbersome. Other examples are picnics, garden parties, and group meetings. In these instances only chairs or benches 65 would be needed. In addition, my tray holder is adaptable for use in moving vehicles such as trains etc. where it would be used for serving passengers. Many other applications are readily apparent.

One of the features and advantages of my invention is 70 that it is adaptable for use without the necessity of securing or clamping it to some solid support. Thus by constructing the holder with a bottom support member, it can be adapted to support part of the person's weight when in use. The user merely opens the holder, sits on 75 the bottom support member, and attaches the tray to it.

The tray holder and tray are then supported firmly by (1) the weight of the user, and (2) by the movable jaw assembly respectively. When the tray is used in moving vehicles such as trains, a feature of my invention is that the bottom support member takes advantage of the cushioning effect of the seat and thus dampens vibrations. Furthermore, the tray is adapted to be supported in a position convenient for serving food and is held in this position by the user sitting on the flat supporting member.

My tray holder can hold any standard tray or any specially built tray and when the tray holder is not in use it may be conveniently folded into a small package for ease in storing.

Other advantages of my tray holder are that it is sturdy, durable, light weight and requires only a fraction of the space per person that would be required by use of the conventional table.

While I have described my invention in detail for the preferred embodiments shown it will be understood that modifications may be made within the scope of the invention as defined by the appended claims.

I claim:

1. A tray support comprising an upright member having two parallel, spaced members, a tray, a movable jaw assembly including spring means for yieldingly clamping and locking an edge portion of said tray on said upright member so as to lock it in a substantially horizontal position at right angles to said upright member, a base of thin, flat material having one end secured to the bottom of said upright member at right angles thereto, and underlying said tray, said base being of insufficient gauge and size to provide a steady support for said tray, particularly

when food is supported thereon, and requiring part of the user's weight thereon to provide a stable support for said upright member and tray, the spacing between said base and tray being greater than the width of the leg of an average person so as to permit sitting on said base to apply part of the user's weight thereon.

5 2. A tray support as recited in claim 1 wherein said base is substantially rectangular, a pair of brackets mounted on said base on which said upright member is pivotally mounted, one of said brackets including a vertical slot for holding said upright member vertically.

10 3. A tray support as recited in claim 1 wherein said movable jaw assembly comprises a handle, a resilient link attached to said handle, and a movable arm adapted to lock said tray, said movable arm being actuated by said resilient link.
